Earl S. Tupper, Smithfield, R. I.

Application October 25, 1956, Serial No. 43,528

Term of patent 14 years

(Cl. D44—18)

Fig. 1

Fig. 2

Fig. 3

Figure 1 is a new view in perspective of a table crumber set, showing my new design;

Figure 2 is a top plan view thereof;

Figure 3 is an end view in elevation thereof, the opposite end view being similar and not shown;

Figure 4 is an exploded view in perspective showing the brush and tray per se;

Figure 5 is a rear view in perspective of the brush shown in Figure 4; and

Figure 6 is an end view in elevation of the brush shown in Figure 5, the opposite end being similar and not shown.

I claim:

The ornamental design for a table crumber set, substantially as shown and described.
